UNITED STATES PATENT OFFICE.

MICHAEL J. ECONOMIDES, OF BROOKLYN, NEW YORK.

HINGE.

Application filed June 30, 1925. Serial No. 40,533.

This invention relates to hinges and particularly to what are known as door hinges, and still more particularly to hinges for the doors of automobiles, an important object 5 being to provide a device of the kind indicated which will permit the door to be readily attached to or removed from the body of the automobile when the door is in a certain position.

Another object of the invention is the provision of a separable door hinge in which the bolt is rigidly carried by one section of the hinge and is adapted to be engaged by the other section at each end thereof when the 15 hinge is in an operative or assembled position.

A further object of the invention is to provide a hinge of the character described composed of a stationary leaf carried by the 20 automobile body and a movable leaf carried by the door, said stationary leaf being constructed by stamping the same from a single piece of sheet material and bending the same into the desired form, and then welding the 25 same at certain points for holding said section in its desired shape or formation.

It is also an object of the invention to provide an improved hinge of this class, which is simple in construction, which can be manufactured 30 economically, and which will be thoroughly efficient, substantial, and practical in use.

With the foregoing and other objects in view, which will be apparent as the description 35 proceeds, the invention resides in the construction and arrangement of parts, as hereinafter described and claimed, it being understood that changes can be made within the scope of what is claimed, without departing 40 from the spirit of the invention.

The invention is illustrated in the accompanying drawings, wherein:

Figure 1 is a perspective view showing my improved hinge applied to an automobile 45 door and body,

Figure 2 is a vertical section taken on line 2-2 of Figure 1, showing the door in a closed position.

Figure 3 is a horizontal section taken on 50 line 3-3 of Figure 2,

Figure 4 is a perspective view of the rear side of the stationary leaf,

Figure 5 is a plan view showing the shape 55 of the material for constructing the stationary leaf before the same is bent or formed in its desired shape,

Figure 6 is a perspective view of the movable leaf carried by the door,

Figure 7 is a vertical section through a slightly modified form of hinge construction, 60

Figure 8 is a horizontal section taken on line 8-8 of Figure 7,

Figure 9 is a fragmentary view showing a portion of the device illustrated in Figure 7 but showing the leaves of the hinge being 65 assembled or disassembled from each other,

Figure 10 is a vertical section through a still further modified form of hinge.

Figure 11 is a horizontal section taken on line 11-11 of Figure 10, and 70

Figure 12 is a fragmentary vertical section similar to the form of my invention illustrated in Figures 1 to 6 inclusive, but showing a slightly modified form of bolt.

In carrying out the invention, the numeral 10 designates the body of an automobile which is provided with a recess 11 for receiving the stationary leaf 12 of my improved hinge, while the numeral 13 designates the door which carries the movable leaf 14 of my device. The stationary leaf 12 is constructed of a single piece of sheet material which is stamped and bent or formed in the desired shape, said stationary leaf being provided with a U-shaped portion 15, which has the pair of spaced walls 16 and 17 and the rear wall 18. Extending away from each other on the outer ends of the parallel spaced side walls 16 and 17 are a pair of flanges 19 and 20, which are received in small grooves 21 and 22 formed in the face of the body 10, so as to lie flush with said face. A plurality of wood screws 23 are positioned through openings 24 formed in the flanges 19 and 20 for holding the stationary leaf connected to the body. 90

Extending upwardly from the lower side wall 17 is an extension 25 which forms a vertical wall at the side of the U-shaped portion 15, while extending downwardly from the upper side 16 is another extension 26 which lies on the outer face of the extension 25 and which also extends under the lower side 17, as at 27, for supporting said side 17. The walls 25 and 26 and the lower side 17 of the U-shaped portion 15 and the portion 27 are welded together or otherwise secured for holding said U-shaped portion in the desired formation. A small extension 28 is provided on one end of the wall 25 which is bent at right angles to said wall for forming an abutment member to be engaged by 100

the movable leaf 14 when the door is in an open position. Extending downwardly from the flange 19 is a narrow strip 29 that is slightly offset, as at 30, and engages the inner 5 face of the flange 20 at one side edge thereof, said strip 29 being secured to the flange 20 by welding, or the like, for also aiding in holding the spaced parallel walls 16 and 17 of the U-shaped portion in proper spaced 10 position. From the foregoing, it can be seen that I have provided a stationary leaf having a pair of attaching flanges and a U-shaped socket formed between said flanges which is formed in such a manner as to provide a substantial rigid structure.

The movable leaf 14 is also provided with a pair of flanges 31 and 32 which are countersunk in the door and secured to said door by means of screws 33. Extending 20 from the flanges 31 and 32 at their connecting portions is a hook-shaped arm 34, which is constructed by forming portions of the flanges 31 and 32 at right angles and securing said right angled portions together in 25 any well known manner. The hook-shaped arm 34 is provided with an enlarged head 35 at its free end through which extends a bolt 36 which is secured to said head in a rigid manner. The bolt 36 has an enlarged 30 head 37 on the upper end thereof, the purpose of which will be understood as the description proceeds.

Extending downwardly through the lower side 17 of the U-shaped portion 15 and 35 through the reinforcing member 27 is an opening 38 which receives the lower end of the bolt 36 carried by the hook-shaped arm 34, while in the upper side 16 of said U-shaped portion is formed an enlarged opening 39 which receives the head 37 of the bolt 36. It can be seen that by providing the openings 38 and 39 in the side walls 16 and 40 17 for receiving portions of the bolt 36 that the free end of the hook-shaped arm 34 is pivoted in the U-shaped portion 15. In order to prevent upward movement of the hook-shaped arm when the door is in any position except the extreme open position, I have provided a downwardly extending 45 flange 40 formed from the upper wall 16 which engages the upper surface of the hook-shaped arm when the door is in a closed or partially closed position, thus 50 eliminating such upward movement of the door and movable leaf 14.

As it is desirable to provide hinges for automobile doors of a separable type, I have provided a slot 41 which opens into the opening 39 in the upper side 16 of the U-shaped portion for permitting the bolt 36 to slide therethrough when the door and movable leaf have been opened and raised so as to disengage the lower end of the bolt 36 from the opening 38 in the lower side 17, 60 while in the flange 19 I have also provided

an enlarged opening 42 slightly above the upper wall 16 so as to permit the head 37 of the bolt to slide therethrough when the bolt 36 is moved forwardly through the slot 41, as shown in dotted lines in Figure 2 of the 70 official drawings. It will be noted that both ends of the bolt 36 are pivotally mounted in the upper and lower side walls 16 and 17 of the U-shaped portion 15 which will eliminate sagging of the door as often occurs in 75 hinges provided with only a depending trunnion for pivotally connecting the two sections of the hinge together.

In Figures 7, 8, and 9 of the official drawings I have shown a slightly modified form, 80 which show a tongue 45 cut from the upper side wall 16 of the U-shaped portion 15 and bent to extend inwardly from the end wall 18 parallel with the upper and lower side walls 16 and 17. The tongue 45 is provided with a cylindrical opening 46 and a slot 47 leading into the opening 46, said slot being provided for permitting the bolt 36 to slide therethrough while the cylindrical opening 46 is provided for receiving the head 37 of the bolt when the device is in an assembled or operative position. It will be noted by referring to the drawings, that I have provided a tongue in this form of my invention for receiving the head of the bolt 36 instead of pivotally supporting the upper end of the bolt in the upper wall 16 of the U-shaped portion. By referring to Figure 9, it will be noted how the two sections of my hinge 90 may be attached or detached from each other.

In Figures 10 and 11 of the drawings, I have shown a further modified form of my invention whereby the bolt 36 having the head 37 is eliminated, and a cylindrical opening 50 is provided in the head 35 of the hook-shaped arm 34 for receiving an upwardly extending pin 51 carried by the lower side wall 17 of the U-shaped portion. In order to prevent the two sections of the hinge from being accidentally disengaged, I have provided a pair of lugs 52 extending in opposite directions from the uppermost portion of the pin 51 for engaging the upper surface of the head 35 to hold said hook-shaped arm 34 on said pin. In the head 35 at the opening 50 therein is provided a pair of grooves 53 which align with the lugs 52 when the hinge is an open position for permitting the hook-shaped arm 34 to be raised for disconnecting the two sections of the hinge. In this form of my invention, it is necessary to space the upper and lower walls 16 and 17 of the U-shaped portion a greater distance apart for permitting the disconnecting of the two sections of the hinge.

I have shown a still further modified form in Figure 12 of the official drawings, which is similar to the form of my invention illustrated in Figures 1 to 6 inclusive, but shows

another head 55 on the bolt 36 arranged above the head 37 for engaging the upper surface of the upper wall 16 of the U-shaped portion, which will act as a means for supporting the hook-shaped arm 34 against binding engagement with the lower wall 17, thus causing the door to swing more easily. In order to permit the movable leaf 14 to be removed from the stationary leaf 12, it is necessary to provide another opening 56 in the flange 19 above the opening 42 for permitting the enlarged head 55 to pass therethrough when the hook-shaped arm has been raised and slid forwardly.

From the foregoing, it can be seen that I have provided a separable hinge for automobile doors which will permit the door to be removed from the body when the same has been swung to its open position, such removal being possible by exerting a slight upward movement of the door and sliding the same away from the body. It is also to be noted that when the two sections are in an assembled position that both ends 25 of the bolt that pivotally connects the same are supported in the U-shaped portion of the stationary leaf, thereby providing a structure which will eliminate to a great extent the sagging of the door.

Having thus described my invention, what I claim as new is:

1. A hinge of the character described comprising a stationary section and a movable section, an arm formed on said movable section, a bolt carried by said arm and extending to each side thereof, an enlarged head formed on the upper end of said bolt, and a pair of spaced plates carried by said stationary section, said spaced plates each having an opening therein, one for receiving the lower end of the bolt while the other receives the enlarged head, said arm being spaced from the plate receiving the enlarged head, said plate receiving the head having a slot formed therein for permitting the movable section to be disengaged from the stationary section upon upward movement to disengage the enlarged head from its opening and sliding movement of said movable section.

2. A hinge of the character described comprising a movable section and a stationary section, an arm carried by the movable section, a pin carried by the arm and extending to each side thereof, a pair of spaced plates arranged on the stationary section, said plates having openings therein for receiving the ends of the pin, said arm being spaced from the uppermost of said plates, means for permitting said movable section to be disengaged from the stationary section by raising and sliding the same away from the stationary section when the movable section is in an open position, and means carried by the uppermost plate for engaging the upper surface of the arm for preventing upward movement of said arm except when said movable section is in an open position.

movement thereof except when the movable section is in an open position.

3. A hinge of the character described comprising a movable section and a stationary section; said stationary section being constructed from a single piece of sheet material stamped and formed to provide a U-shaped portion, a pair of flanges extending from the outer ends of the side walls of said U-shaped portion, an extension on one side of one side wall which is bent at a right angle to form an end wall, said side walls having openings therein; an arm carried by said movable section, and a bolt carried by said arm and received in the openings in the side walls of said U-shaped portion for pivotally connecting the movable section to the stationary section.

4. A hinge of the character described comprising a movable section and a stationary section; said stationary section being constructed from a single piece of sheet material stamped and formed to provide a U-shaped portion, a pair of flanges extending from the outer ends of the side walls of said U-shaped portion, an extension on one side of one side wall and engaging the outer surface of the other side wall of said U-shaped portion for supporting the same, said side walls having a pair of openings therein; an arm carried by said movable section, and a bolt carried by said arm and received in the openings in the side walls of said U-shaped portion for pivotally connecting the movable section to the stationary section.

5. A hinge of the character described comprising a movable section and a stationary section; said stationary section being composed of a single piece of sheet material stamped and formed to provide a U-shaped portion, a pair of flanges extending from the outer ends of the side walls of said U-shaped portion, an extension on one side of one side wall which is bent at a right angle to engage the other side wall for forming an end wall, another extension formed on the other side wall and bent to engage the outer surface of said first mentioned extension and to engage the outer surface of the side wall carrying said first mentioned extension to support same, and a depending flange extending from the opposite side of the side wall having said last mentioned extension, said side walls having openings therein; an arm carried by said movable section; a bolt carried by said arm and being received in the openings in the side walls of the U-shaped portion for pivotally connecting the movable section to the stationary section, said depending flange engaging the upper surface of the arm for preventing upward movement of said arm except when said movable section is in an open position.

6. A hinge of the character described comprising a stationary section and a movable

section, an arm formed on said movable section, a bolt carried by said arm and extending to each side thereof, a pair of plates formed on said stationary section in spaced relation, said plates having openings therein for receiving the ends of said bolt for pivotally connecting the movable section to the stationary section, and a head formed on the upper end of said bolt and spaced from said arm for engaging on the upper surface of the uppermost of said plates for preventing fric-

tional engagement of the arm with the lowermost of said plates, the uppermost of said plates having a slot formed therein and extending to the opening therein for permitting said movable section to be slid from engagement with the stationary section after upward movement of said movable section. 15

In testimony whereof, I have affixed my signature.

MICHAEL J. ECONOMIDES.
